UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

WATER-TIGHT RECEPTACLE AND PLUG THEREFOR.

Application filed August 7, 1918. Serial No. 248,684.

To all whom it may concern:

Be it known that I, REUBEN B. BENJAMIN, a citizen of the United States, residing at Chicago, in the county of Cook and State 5 of Illinois, have invented new and useful Improvements in Water-Tight Receptacles and Plugs Therefor, of which the following is a full, clear, concise, and exact description, reference being had to the accompanying drawing, forming a part of this specification.

My invention relates to an improved water-tight receptacle and plug therefor, one object of the invention being to produce a device of this kind from which moisture, vapors, gases, and the like are effectually excluded, so that it will be suitable for use in exposed places, such as on ship-board.

Another object is to produce a device in which it is possible to connect the parts without twisting the conductors.

Another object is provide means whereby any strain caused by the conductor-cords being pulled or jerked is taken by the external or housing members of the device, instead of by the receptacle contacts.

Another object is to provide an improved construction for the insulating and current-carrying parts of the plug, permitting the conductors to be readily connected.

In the accompanying drawings—

Fig. 1 is an elevational side view of a water-tight receptacle with a screw-cap in place;

Fig. 2 is a view showing the device with the cap removed and the plug inserted, the outlet-box or casing of the receptacle being shown in section;

Fig. 3 shows an axial section of the plug, the section being taken on the line 3—3 of Figs. 5 and 7;

Fig. 4 shows an axial section of the plug, the section being taken on the line 4—4 of Figs. 5 and 7;

Fig. 5 is an end view of the plug;

Fig. 6 is a broken elevational view of the part of the plug which enters the threaded socket of the receptacle;

Fig. 7 is a plan view of the under side of the inner or lower insulating base member of the plug, showing the binding-terminal;

Fig. 8 is a plan view of the under side

of the outer or upper insulating base member of the plug;

Fig. 9 is a cross-sectional view of the cord-gripping portion of the plug, the section being taken on the line 9—9 of Fig. 3;

Fig. 10 is a bottom plan view of the insulating base of the receptacle and the parts carried by this base, looking into the threaded socket, the insulating sleeve which surrounds the threaded shell contact being omitted; and

Fig. 11 is an axial sectional view of the same, the section being taken on the line 11—11 of Fig. 10, the insulating sleeve being shown in place in this view.

In the several figures of the drawings, in which like reference numerals indicate the same parts throughout, the casing or outlet-box comprises a main body portion 20 and a cover portion 21, which is held to the body portion by screws 22, a water-tight joint 70 being made between these parts by means of a rubber gasket ring 23. The cover portion 21 of the casing is provided with an externally-threaded neck 24, through which the plug of the device is inserted into the threaded socket-shell. When it is not desired to use the device as a means for supplying current to translating devices, the plug will be withdrawn from the socket and a cap 25, which is internally screw-threaded, 75 80 85 may be placed in position on the neck and maintains the device water-tight. To prevent the cap 25 from becoming lost, it is connected to the casing by means of a short chain 25a.

When it is desired to insert the plug into the casing this cap 25 is removed. The plug, after being inserted, is securely held in position by means of a threaded ring 26 which is swivelingly carried by the casing of the 95 plug and which takes the place of the cap 25.

Before describing the details of the plug portion of the device, the receiving-socket and other parts which are contained within the casing of the receptacle will first be 100 described.

A base 27 formed of suitable insulating material is secured in the casing by means of screws 28, which pass through suitable openings 29 and 30 in the base 27. These 105 openings are key-hole shaped, so that the screws do not need to be removed entirely when it is desired to take the base out of

the casing. To prevent rotation of the base 27 and consequent turning under the heads of the screws 28, which might result in the base becoming detached, the smaller or restricted end of each key-hole-shaped opening is countersunk to receive the head of the screw. This leaves a projection 28^a on each side of the opening, beyond which the screw-head cannot pass.

- 10 The threaded contact shell 31 is held in position on the insulating base 27 by means of a pair of screws 32 and 33, which extend through the base into small plates 34 and 35. These plates are located in the contact shell 31, the latter being provided with an inturned flange 36, through which the screws pass into the plates 34 and 35. A third screw 37 passes through the insulating base 27 and through the flange 36 of the shell contact 31, and enters a threaded opening in a binding-terminal plate 38. This binding-terminal plate passes through a slit in the side of the shell contact and is provided with binding-screws 39 and 40.
- 15 25 Electrical connection is made between one of the leading-in conductors and the threaded contact shell 31 by means of this terminal plate 38.

The center contact corresponding to the 30 threaded outer contact 31 is formed by a spring plate 41, which is held in position by means of a screw 42, which passes through the insulating base 27 into a binding-plate 43. This binding-plate is provided with a pair of binding-screws 44 and 45. An internally-threaded ring 46, formed of porcelain or other suitable insulating material, is screwed upon the outside of the socket shell contact 31 and extends a 35 short distance beyond the outer edge of the latter. When connection is to be made between the wires and the binding-terminals of the socket, this threaded ring 46 is removed. The inner end of the ring 46 is 40 enlarged to give it a sufficient diameter to extend well beyond the outer ends of the binding-plates 43 and 38.

The insulating base 27 is formed with a 45 pair of lugs 47 and 48, which extend outwardly from the face of the member 27, and when the insulating ring 46 is screwed upon the shell contact 31 it is limited by the lugs 47 and 48.

Referring now to the plug portion of the 50 device, the latter includes an outer casing or housing 50. This housing is expanded at its forward end to provide a comparatively large chamber 51, in which is disposed the insulating base 52. The base 52 is secured in the housing 50 and has its under side formed with recesses in which are located the binding-terminals. Another insulating member comprising a cylindrical block 53 forms the portion of the plug 55 which carries the outer contact member

and the end contact member which co-operate with the contacts of the receptacle when the parts are put together. The center contact member of the plug comprises a plunger 54, which is urged outward by a 70 spring 55. The plunger 54 is guided in an opening or recess 56 in the insulating block 53, by a hollow shell 57, which works up and down in the opening 56 in the block and contains the outer end of the spring 55. 75 The inner end of the spring 55 is seated against a bushing 58, which forms a guide for the inner end of the plunger 54. This bushing is in electrical connection with a plate 59, which lies in a shallow recess in 80 the end of the insulating block 53 and is held in place therein by the bushing 58, which is expanded or clinched over at its inner end upon the plate 59. The plunger 54 is limited in its outward movement by 83 being expanded or headed at its inner end 54^a.

The outer contact of the plug comprises a metallic shell or ring 60 which surrounds the cylindrical insulating block 53 and also 90 a pair of bow-shaped resilient members 61 and 62, held in place by the metallic ring 60. The members 61 and 62 lie in slits in the ring 60 and make direct contact with the inner surface of the threaded shell contact 31 of the receptacle when the plug is inserted thereinto. The metallic shell 60 is held in position on the block 53 by having its ends inwardly flanged at 63 and 65, the former flange lying between the two insulating members 52 and 53 of the plug. A metallic plate-ring 64 is held in place by the flange 63 and is, of course, in electrical communication with the shell 60. Where the upper end of the shell 60 is turned over upon the end of the insulating member 53 at 65, it is formed at two opposite points with tongues 66 and 67 which extend downwardly in line with the slots 61^a and 62^a in the sides of the member 53, which are provided to accommodate the resilient contact strips 61 and 62. When the plug is thrust into the socket member of the receptacle the strips 61 and 62 are caused to flatten slightly, being bent inwardly toward the member 53, and are pressed into firm electrical contact with these tongues 66 and 67.

The insulating member 52 carries the binding-terminal plates upon its lower or inner side. These binding-terminal plates, best seen in Fig. 7, are held in position by screws which pass up into the plate 59 and ring 64 on the under or inner side of the member 53. The terminal plate 70 is held in place by a screw 71, which passes through the base 52 into a threaded opening 71^a in the conducting plate 64. The terminal plate 70 is provided with the usual binding-screw 72. A screw 73 similarly holds in

place the binding-terminal plate 74 and electrically connects it with the plate 59 on the under side of the member 53, electrical connection thus being made between the terminal plate 74 and the center contact 54 of the plug. The terminal plate 74 is also provided with a binding-screw 75. To further aid in mechanically holding the parts of the plug together, a pair of screws 76 and 77 are provided, which also pass up into the conducting ring 64.

The parts of the plug which carry the current-conveying members and binding terminals, when held together by the various screws above described, constitute a unit which may be removed from the casing or housing of the plug for the purpose of wiring the device. These parts are normally held in position in the housing by means of a pair of screws 78 and 79, which extend through notches 80 and 81 in the edge of the inner or lower insulating base member 52.

The inner wall of the housing of the plug, at its upper end, is made tapering or substantially cone-shaped. A cone-shaped soft rubber ring 82 is arranged in this part of the housing and forms a gasket provided with a water-tight joint with the covering of the conductor cords, to exclude moisture from the current-carrying parts of the device. The inner end of this ring is provided with a laterally-extending flange having substantially the diameter of the inside of the portion 51 of the casing 50.

The conductor-cord extends up through the neck 83 of the housing 50 and through the ring 82, where the ends of the conductors are secured to the binding-screws on the under side of the member 52. These connections are made while the current-carrying parts of the plug are removed from the casing, which may be done, as hereinbefore explained, by the removal of the screws 78 and 79. After the connections are made and the current-carrying parts of the plug are reinserted in the casing, the tightening of the screws 78 and 79 tends to force the rubber ring 82 down into the tapering mouth of the housing and to press the same in against the covering of the cord. At the same time the flange on the upper end of the rubber ring is pressed into close contact with the under side of the base member 52. The enlarged upper portion of the rubber gasket ring thus forms a cover for the depressions in the base member 52 in which the binding terminals are located, whereby moisture is prevented from getting to these parts when the plug is not in use.

On the lower side of the insulating member 52 there is provided a wedge-shaped extension 82^a, which is intended to separate the two conductors of the cord and force them against the inside of the rubber ring 82.

The lower end of the neck portion 83 of the housing of the plug is provided with means for gripping the cord to take the mechanical strain caused by pulling or jerking upon the cord. This cord-grip is formed by slitting the neck 83 longitudinally into preferably six parts, so that the tongues or fingers thus formed may be forced inwardly against the cords. A taper-threaded compression-ring 84 is arranged to be screwed up on the lower split end of the neck 83 and to contract the same against the covering of the cord.

The upper edge of the housing is formed with a flange 85, which extends therearound and holds in place the swivel ring 26, the latter having an inturned lower edge 86 for engagement under the flange 85. The ring 26 is internally threaded to engage the threads on the neck 24 of the receptacle casing.

When it is desired to connect the plug with the receptacle portion of the device, the cap 25 is first removed by unscrewing it and the plug is brought into position to cause the contact-carrying part of the latter to enter the threaded socket. Rotation of the plug member is not necessary in order to make electrical connection, as the outer contact member of the plug is of such form that it may enter straight into the socket and make good electrical connection therewith.

In order to hold the parts in mechanical and electrical connection, the threaded ring 26 is revolved to screw the same upon the neck 24 of the receptacle casing. A sealed joint is made between the plug housing 50 and the receptacle casing 21 by a compressible gasket-ring 88 which is clamped between these parts when the ring is screwed up.

I claim as new and desire to secure by Letters Patent of the United States:

1. An electrical connecting device comprising a housing provided with means for securing it to a main support, an insulating base member disposed in said housing, binding-terminals carried by said base member, an insulating block carried by said base member and extending beyond the forward edge of the housing, a center contact carried by said block, and an outer conducting shell carried by said block and having its rearward edge flanged inwardly and confined between said block and said base member.

2. An electrical connecting device comprising a housing provided with means for securing it to a main support, an insulating base member disposed in said housing, binding-terminals carried by said base member, an insulating block carried by said base member and extending beyond the forward edge of the housing, a center contact carried by said block, and an outer contact member comprising a ring surrounding said block, said ring having an inturned inner edge, a

conducting plate clamped between said edge and said block, and means for holding said insulating parts together, comprising means extending through said insulating base member into said clamping plate.

3. An electrical connecting device comprising an insulating base member, binding-terminals carried by said base member, an insulating plug, a conducting shell on said plug having its inner end flanged over the end of the plug, said shell having a plurality of slits, and a strip of conducting material lying in each of said slits and held between said shell and plug and adapted for engagement with the outer contact of a socket.

4. An electrical connecting device, comprising an insulating base member, binding-terminals carried by said base member, an insulating plug, a conducting shell on said plug having its inner end flanged over the end of the plug, said shell having a longitudinal slit, a strip of yielding conducting

material lying in said slit and in electrical communication with said shell and held between said shell and plug, and adapted for 25 engagement with the outer contact of a socket, and means for securing said plug and said insulating member together with the conducting plate in electrical communication with one of the binding-terminals. 30

5. An electrical connecting device comprising an insulating plug member, a conducting shell on said member, said shell having a longitudinal slit, said shell having also an inturned projection opposite said slit, and a yielding strip of conducting material lying in said slit and having its middle portion bowed outwardly to engage the outer contact of a socket, and arranged to be pressed into engagement with said inturned 40 projection.

In witness whereof, I have hereunto subscribed my name.

REUBEN B. BENJAMIN
